RADIO RECEIVING SYSTEM

Application filed April 30, 1930. Serial No. 448,543.

This invention relates to radio receiving systems and particularly to systems for receiving extremely high frequency continuous wave telegraph signals.

5 A broad object of the invention is to provide a receiver which is extremely sensitive and selective and yet stable in operation and simple in construction.

In brief, the receiver in accordance with 10 the present invention comprises a regenerative amplifier and a detector tube with a chopper (for breaking up the received continuous wave) inserted between the amplifier and the detector tube.

15 The single figure of the drawing constitutes a schematic diagram showing the preferred circuit of the invention.

Referring to the drawing a detector tube 2 has, as an element of its input circuit, a 20 coil 1, which is connected between the cathode 3 and grid 4 of the tube. Coil 1 is inductively coupled to a second coil 5, which is, in turn, coupled to an antenna circuit 6.

To reduce the losses in the receiving circuit, a regenerative tube 11 is provided. The 25 input circuit of this tube, comprises cathode 12, coil 5 and grid 13, and the output circuit comprises anode 14, coil 15, series condenser 20, and cathode 12. The cathode 12 is connected to a source of heating current 16, and 30 a source of anode potential 18 is connected to the lower terminal of coil 15 through a radio frequency choke coil 19. Condenser 20 serves to vary the inductive reactance of 35 the anode circuit by compensating in part for the reactance of coil 15. At the extremely high frequencies at which this system is designed to operate, the inherent capacity between the grid 13 and anode 14 of 40 tube 11 provides a sufficiently low impedance path to feed back energy from the output to the input circuit of this tube and produce regeneration, providing the constants of the circuit are properly proportioned.

45 Although detector tube 2 may be operated in any conventional fashion, it has been found to work particularly well in this circuit with the grid return connected directly to the negative terminal of the filament and 50 with the anode return connected directly to

the positive terminal of the filament. A bypass condenser 22 provides a path of low impedance for the radio frequency current component in the output of the detector, and a radio frequency choke coil 23 serves to 55 keep this component from the audio frequency circuit (not shown), which may be of any well known type and is coupled to the output circuit of detector tube 2 through an audio frequency transformer 24. A chopper, 60 schematically shown at 25, is connected in series with a condenser 26 across the input terminals of the detector tube. Chopper 25 may consist of any suitable contact device 65 capable of opening and closing its contacts at a tone frequency.

In operation, the circuit is tuned to the frequency of the desired wave by adjusting condensers 9 and 20. Since the setting of condenser 20 also determines the amount of regeneration produced by tube 11, these two controls (condensers 9 and 20) are manipulated until a setting is obtained which gives the proper tuning and also the proper amount of regeneration. With tube 11 adjusted to a 70 highly regenerative condition, the energy fed back through the tube capacity from the output circuit to the input circuit is sufficient to more or less neutralize the resistance of the receiving circuit. Hence, any slight potential 75 applied to antenna 6 by an incoming radio wave produces a relatively large current in coil 5. This induces corresponding currents in coil 1 and the potential thereby produced in this coil is applied to the tube 2 during the intervals when the chopper contacts 25 are open. However, when the chopper contacts 25 close, a path is provided in shunt to coil 1, through condenser 26. This not only serves to shunt some energy from the input circuit of the tube 2, but tends to tune the 80 whole receiving circuit to a longer wavelength, thereby reducing the sensitivity of the receiver to the continuous wave being received. Therefore, when the chopper contacts are closed, a reduced potential is applied to the input circuit of detector tube 2. Since 85 the detector tube acts as a rectifying device, alternating current of the chopper frequency flows in its output circuit whenever contin- 90

uous waves are being produced in coil 1. However, when no such waves are produced, the grid of detector tube 4 is at the same potential as the cathode 3 and the operation of chopper 25 has no effect on the steady-state current flowing in the primary of audio frequency transformer 24.

Condenser 26 may be replaced with a resistance, under which conditions it has been found to operate equally well.

It is found that when operating at any one frequency, there is an optimum number of turns in coil 1 which gives best results. For this reason an adjustable tap switch 28 is provided to adjust this coil to operate at different frequencies.

The source of continuous waves to be amplified and detected need not necessarily be an antenna of the particular form shown in the drawing, but may be of any suitable type for the reception of short waves. Whatever type of antenna is provided, however, it is preferably loosely coupled to coil 5.

I claim:

1. In a high frequency carrier receiving system, a source of continuous wave signals, detecting means, coupling means between said detecting means and said source, regenerative means including a three-element vacuum tube, the input circuit of which is also coupled to said source for increasing the transfer efficiency of said coupling means and means comprising a chopper and an impedance element in series adapted to shunt high frequency energy from said detector intermittently at a tone frequency.

2. In a receiving system, a source of continuous waves, a three-electrode vacuum tube having its input circuit coupled to said source, means for feeding back energy from the output circuit to the input circuit of said tube whereby it functions regeneratively, a detector having an input circuit and an output circuit, the input circuit of said detector being coupled to said source, and chopper means shunting the input circuit of said detector for interrupting at a tone frequency the application of continuous waves to said detector.

3. In a receiving system, a source of continuous waves, a three-electrode vacuum tube having its input circuit coupled to said source, means including the grid-anode capacity of said tube for tuning the input and output circuit of said tube as a unit to the frequency of said waves, a portion of said means controlling the amount of energy fed back from the output circuit of said tube to the input circuit through said grid-anode capacity, a second three-electrode vacuum tube having as a portion of its input circuit a coil inductively coupled to the input circuit of said first tube, a path shunting said coil, said path including a condenser in series with a tone frequency interrupter.

4. In a high frequency receiving system, a source of continuous waves, a vacuum tube oscillator coupled to said source, means for tuning said oscillator to a highly regenerative condition so as to more than neutralize the resistance thereof, a detector having an input circuit and an output circuit, coupling coils in each of the circuits of said source, said oscillator and the input circuit of said detector respectively, said coupling coils mutually reacting with one another, and chopper means shunting the input circuit of said detector, said chopper means being adapted to successively tune and detune the receiving system at an audible frequency.

In testimony whereof, I have hereunto set my hand.

HORACE E. OVERACKER.
